(57) **CLAIM**

The ornamental design for a watch case as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of a watch case showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The stylized "LV" shown on the crown of the watch case and the stylized flower designs shown on the edges of the watch dial are registered trademarks of Louis Vuitton Malletier. The broken lines depict portions of the watch case that form no part of the claimed design.
